CHARLES SLAUSON BOARDMAN, OF BUFFALO, NEW YORK, ASSIGNOR TO LACKAWANNA STEEL COMPANY, OF LACKAWANNA, NEW YORK, A CORPORATION OF NEW YORK.

INTERLOCKING SHEET PILING.

1,411,905.

Specification of Letters Patent. Patented Apr. 4, 1922.

Application filed May 19, 1920. Serial No. 382,552.

To all whom it may concern:

Be it known that I, CHARLES S. BOARDMAN, a citizen of the United States, residing at Buffalo, in the county of Erie and State 5 of New York, have invented new and useful Improvements in Interlocking Sheet Piling, of which the following is a specification.

This invention relates to steel sheet piling of the type known as interlocking sheet piling which is built up of separable piling sections or piles which are preferably integrally rolled and provided with interlocking elements or flanges at the vertical marginal sides or edges thereof and adapted when the 10 piles are driven to interlock with co-acting flanges of an adjacent section and thereby form a continuous wall of piling. Such piling has been very successful and is extensively used, particularly in the construction 15 of coffer dams, open caissons, retaining walls for foundations, bulkheads, etc. where it is essential that water, earth and other material shall be retained thereby.

As has been demonstrated by commercial 20 use, sheet piling to be fully successful, must successfully meet the requirements of various installations and in particular, must be adapted for subaqueous installations, such as coffer dams and retaining walls employed in 25 the building of bridge piers, dock walls, etc., where work must be done below water level. The piling sections of the present invention are designed particularly with a view to obtaining the maximum degree of water tightness 30 in the interlocks and the improved features thereof are desirably embodied in the type of interlocking joint known as the double interlock type, characterized by having each edge of the web provided with double 35 interlocking members, comprising a hook and a guard flange which produce a particularly strong interlock and one which has proven very successful owing to the water tight qualities of the interlock so formed.

40 The piling of the present invention is preferably embodied as a modification of the so-called "Lackawanna piling" of the double interlocked type described and consists in a suitable modification thereof whereby supplemental grooves are provided in the interlocks which grooves are desirably formed in 45 the outer surface of the hook flange and directed toward the wall or surface of the co-acting flange of an adjacent interlock so as 50 to provide a supplemental sealing pocket

and additional points of contact between the flanges of the interlock thereby greatly to contribute to the water tight qualities thereof. By this means, there are formed supplemental pockets or grooves within the 60 main sockets or pockets within which slit or other material will readily accumulate to seal said pockets and the additional points of contact between the engaging flanges, acting under the pressures exerted on the 65 pile sections, will provide a plurality of sealing points thereby insuring the effectiveness thereof in preventing leakage through the joints.

A further important feature of the present 70 invention resides in the improved form and arrangement of the interlocking flanges whereby not only are the aforesaid water tight features incorporated therewith, but in addition, the strength of the interlock 75 formed thereby is materially increased and the pull on the piling elements, tending to separate the interlocks, is resisted by the hooks which are reinforced in the line of longitudinal pull thereon and further have 80 their opposed surfaces or contact faces approximately perpendicular to the neutral axis of the wall.

Desirable embodiments of the present invention are illustrated in the drawings herein 85 with, wherein the aforesaid and other valuable features of the invention are illustrated and wherein the reference characters of this description are applied to the corresponding parts in the several views. Therein:— 90

Fig. 1 is a plan view of a piling wall formed of the improved sections of my invention.

Fig. 2 is a perspective view thereof;

Fig. 3 is a plan view of an approved installation thereof illustrating the sealing action of the improved interlocks under the lateral pressures on the pile sections.

Fig. 4 is a plan view of a desirable modification embodying important features of 100 my present invention;

Fig. 5 is a perspective view thereof, and

Fig. 6 is a plan view illustrating a further modification embodying the features of my invention.

105 In the preferred embodiment of the invention here illustrated, each piling section consists of a web 1 having on each vertical marginal edge thereof a hook or inner flange 2 and a curved guard or outer flange 3. 110

- The hook and guard flanges 2 and 3, which may be termed respectively the "thumb" and the "finger flanges," are relatively arranged so as to form, or to enclose, a groove 5 or pocket 5 which is sufficiently large to receive freely therein the hook or enlargements 6 of the thumb flange on the adjacent pile. The slight freedom so afforded, permits free driving, and the enlarged pockets 10 provide depositories for the reception of displaced material and permit of sufficient, but not excessive, longitudinal and lateral movement of the hook within the groove so as to allow for a limited angular adjustment of the sections.

As shown, the grooves or pockets have a longitudinal mouth or opening 7 formed between the opposed surfaces of the hook 6 and the ends of the finger flanges which are 20 somewhat less in width than the greatest internal width of the pocket and of lesser width than that of the hook portion of the thumb flange received within the pockets whereby the interlock is formed. By this 25 arrangement it results that the piles can only be interlocked vertically and also that they can only be separated longitudinally of the wall by a strain of sufficient strength to distort both flanges on each of the two 30 adjacent piles forming the interlock in question.

In accordance with the present invention, the enlargement or hook portion 6 of the thumb flange is provided with an inwardly 35 directed shoulder or contact surface 8 adapted to engage with the corresponding surface of the thumb flange of an adjacent section so as to resist longitudinal separation. The hook enlargement 6 is further provided with 40 radially extending shoulder extensions 9 and 10, the outwardly directed or engaging surfaces of which are arranged on a radius approximately corresponding to the curvature of the inner surfaces of the guard flange 45 3, so that both of said extensions are adapted to bear upon said inner curved surfaces of the guard flanges at the same time. Intermediate of the extensions 9 and 10, the enlargement 6 is formed of concave curvature 50 thereby, when considered in conjunction with the inner curved surfaces of the guard flange of an adjacent section, forming a supplemental pocket or groove 11 within the main pocket or groove 5. The surface 55 of the enlargement 6 intermediate of the extension 9 and the hook proper is desirably of concave curvature at 12 thereby to reduce the weight of the metal and correspondingly to enlarge the inner end of the 60 pocket 5 to afford sufficient space to receive displaced material during driving.

In the arrangement as shown, it will be noted that the radial extensions 9 and 10 of each of the hooked enlargements of the interlocked sections are arranged in corelation

whereby they will simultaneously engage with the curved inner surfaces of the guard flanges co-acting therewith, whereby, when the interlocks are tightened up under lateral pressures, there will be at least four 70 points of line contact within the interlock and when similarly tightened up under longitudinal stress, there will be said four points of line contact in addition to engagement of the contact surfaces 8-8. By this 75 arrangement as will be readily appreciated, there is attained a maximum degree of water tightness which is further insured by the presence of the supplemental pockets 11-11 which provide additional depositories for 80 silt and mud or for other filler material thereby further contributing to the means afforded for sealing of the interlock. The means thus operating to insure water tightness comprises at least four or five points of 85 line contact between the flanges of the interlocks plus the sealing effect occurring by reason of the main pockets 5-5 supplemented by the smaller pockets or grooves 11 whereby maximum provision is made therefor and 90 effective sealing of the interlocks attained.

A further important advantage resulting from my improved form of piling interlock is obtained by reason of the presence and relative position of the shoulder extension 9 95 with reference to the hook proper of the thumb flange. As will be readily appreciated, tensional stresses on the piling elements, that is, stresses substantially longitudinal of the web and wall produce a tendency to bend or straighten out the hook flanges in addition to subjecting said flanges to shearing stresses. In resisting such stresses the shoulder extensions 9 of the improved interlock afford reinforcing enlargements thereagainst and further, by reason of the engagement of the outer surfaces of said extensions with the guard flanges of adjacent elements said flanges have a bearing thereon so as to resist under compression deformation of the hooks. In consequence the 100 interlock so formed is of exceptional strength.

As illustrated in Figure 3 wherein there is shown the use of a piling wall reinforced by waling timbers, it will be noted that by the arrangement of the similar flanges of each interlock on the same side of the web of each section, that as a result, the alternate piling sections only will bear against the timber. This arrangement, whereby the 110 alternate sections only engage the waling timber by means of their guard flanges is instrumental in obtaining an effective water tight seal in the interlock. In so functioning the intermediate piling elements or sections having their hook flanges directed toward the supporting timber are acted upon by the external pressures and said sections are shiftable as a whole relatively to the supported sections and timbers whereby, un- 115 120 125 130

der the external pressures, they will be forced into tight sealing contact at the interlocks with the adjacent and supported sections.

- 5 As will be appreciated, the described improvements of my present invention may be modified in form and arrangement without departing from the scope thereof as defined in the appended claims. For instance, in
 10 Figs. 4 and 5 there is shown a simple and desirable modification of the well known "Lackawanna" type of piling wherein the thumb or hook flange 6 is modified to have embodied therein the supplemental longitudinal channel or groove 14 arranged whereby its open side will be opposed to and closed by a portion of the adjacent section interlocked therewith, thereby to provide the described supplemental pocket in the interlock.
 15 The improved form of Figs. 4 and 5 is particularly desirable in that the section may be rolled by a simple modification to the rolls for producing the standard sections as now rolled. As will be recognized in this
 20 form the shoulders 9 and 10 result from the formation of the groove 14 and provide the plural lines of contact in the interlock for contributing to the water tightness as hereinbefore described.
 25 In Fig. 6 a further modification is illustrated which conforms closely to the form of Fig. 1 but wherein the shoulder 10 at its inner side is of convex curvature and a continuation of the normal curvature of the
 30 inner portion of the thumb flange.
 Other and important features of my improved piling sections as disclosed reside in the arrangement and proportioning of the metal of the interlocks whereby the latter
 35 under longitudinal stress will offer resistance to separation of the interlock nearly equal to the tensional strength of the web portion of the section; the arrangement and distribution of the metal of the interlocks
 40 whereby the opposing surfaces of the hook enlargements and the guard flanges will engage simultaneously so as to produce a plurality of points of contact both for resistance to separation and to secure greater
 45 water tight values in the interlock and, moreover, in the proportioning of the interlocking flanges with reference to the grooves thereof whereby angular adjustment of the section will be permitted such as illustrated
 50 at the righthand portion of Figure 1 from which it will be noted that the interlocks permit of angular adjustment of the adjacent sections to the extent of about 20° to either side. The flanges of the interlocks
 55 are further so proportioned so as to insure easy driving and pulling of the pile elements by reason of the fact that there is a slight freedom of the hook enlargements within the grooves and the area of contact between
 60 the respective flanges is reduced to a mini-
 65 mum so that there is no undue friction. A further important feature present in the improved interlock disclosed, consists in the relative proportioning of the grooves or sockets with reference to the interlocking flanges whereby the sockets provide sufficient space to receive the material displaced in driving.
 This application embodies the substance of and is a continuation in part of my co-pending application, Serial No. 284,630, filed March 24, 1919.
 Having now particularly described and ascertained the nature of my said invention and in what manner the same is to be performed, I declare that what I claim is:
 1. Steel sheet piling composed of interlocking sections, each section comprising a web having interlocking flanges along each vertical marginal side edge thereof adapted for interlocking engagement with complementary flanges of an adjacent section and at least one of said interlocking flanges at each marginal edge being formed with a plurality of shoulder extensions adapted to engage a laterally opposed surface of an adjacent section substantially as described. 85
 2. Steel sheet piling composed of interlocking sections, each section comprising a web having interlocking flanges along each vertical marginal side edge thereof adapted for interlocking engagement with complementary flanges of an adjacent section, the flanges of at least one edge of said section being formed to provide an enlarged pocket to receive the flange of an adjacent section and to provide a space for displaced material and at least one of the interlocking flanges at each marginal edge being formed with laterally directed shoulder extensions adapted simultaneously to engage the surface of a co-acting flange of an adjacent section and providing a supplemental pocket or groove between said shoulder extensions, substantially as described. 95
 3. Steel sheet piling composed of interlocking sections, each section comprising a web and having interlocking flanges along each vertical marginal side edge thereof to engage with complementary flanges of an adjacent section to form an interlocking connection therewith, one of said flanges at each marginal edge having a surface arranged to oppose lateral displacement of the interlocked flange of an adjacent section and the coacting flange of said interlock being provided with a plurality of shoulder extensions adapted to engage with laterally opposed surface of the first named flange of an adjacent section, substantially as described. 105
 4. Steel sheet piling composed of interlocking sections, each section comprising a web and having interlocks along each marginal side edge thereof adapted to inter- 115
 120
 125
 130

lock with complementary interlocks of an adjacent section, said interlocks being each composed of coacting hook and guard flanges adapted to inclose a socket formed thereby to receive a hook flange of an adjacent section and at least one flange of each interlock being provided with plurality of laterally directed shoulder extensions adapted simultaneously to engage an opposed surface of a flange of an adjacent section interlocking therewith substantially as described.

5. Steel sheet piling composed of interlocking sections, each section comprising a web having interlocks along each marginal side edge thereof and adapted for interlocking engagement with an adjacent section, each of said interlocks being formed of hook and guard flanges formed to inclose between them a socket or enlarged groove adapted to receive therein a hook flange of an adjacent section, and said hook flanges having a plurality of laterally directed shoulder extensions directed toward the inner surface 20 of the guard flange of an adjacent section to coact therewith in forming a supplemental pocket or groove between said extensions substantially as described.

6. Steel sheet piling composed of interlocking sections, each section comprising a web and having interlocks formed at the marginal side edges thereof, said interlocks consisting of hook and guard flanges formed to inclose therebetween an enlarged groove or socket adapted to receive therein the hook flange of an adjacent section, and said guard flanges having their inwardly directed surfaces of curved contour and the curvature thereof being such that when the sections are interlocked the curvature of said surfaces of the guard flanges of adjacent sections approximates an arc from a mutual axis and said hook flanges being each provided with shoulder extensions substantially radial to said mutual axis and at their outer edge surfaces adapted to engage the inwardly directed curved surfaces of said guard flanges substantially as described.

7. Steel sheet piling composed of interlocking sections, each section comprising a web and having interlocks formed at the marginal side edges thereof, said interlocks consisting of hook and guard flanges formed to inclose therebetween an enlarged groove or socket adapted to receive therein the hook flange of an adjacent section, and said guard flanges having their inwardly directed surfaces of curved contour and the curvature thereof being such that when the sections are interlocked the curvature of said surfaces of the guard flanges of adjacent sections approximates an arc from a mutual axis and said hook flanges being each provided with shoulder extensions substantially radial to said mutual axis and at their outer edge

surfaces adapted to engage the inwardly directed curved surfaces of said guard flanges and said hook flanges being formed with grooves intermediate of said shoulder extensions adapted in connection with the coacting flange of an adjacent section to form supplemental sealing pockets, substantially as described.

8. Steel sheet piling composed of interlocking sections, each section comprising a web and having interlocks formed at the marginal side edges thereof, said interlocks consisting of hook and guard flanges formed to inclose therebetween an enlarged groove or socket adapted to receive therein the hook flange of an adjacent section, and said guard flanges having their inwardly directed surfaces of curved contour and the curvature thereof being such that when the sections are interlocked the curvature of said surfaces of the guard flanges of adjacent sections approximates an arc from a mutual axis and said hook flanges being each provided with shoulder extensions substantially radial to said mutual axis and at their outer edge surfaces adapted to engage the inwardly directed curved surfaces of said guard flanges and said hook flanges being formed with grooves intermediate of said shoulder extensions adapted in connection with the coacting flange of an adjacent section to form supplemental sealing pockets, substantially as described.

9. Steel sheet piling composed of interlocking sections, each section comprising a web having interlocks along the marginal edges thereof to engage with complementary interlocks of an adjacent section, each of said interlocks being formed of coacting hook and guard flanges adapted to provide a socket or groove therebetween to receive the hook flange of an adjacent section, said hook flanges being provided with hook portions providing shoulders opposing longitudinal separation and shoulder extensions formed on said hook flanges outwardly extending from said hook portions and adapted to engage a surface of the adjacent section to reinforce said hook portions against deflection under longitudinal stress substantially as described.

10. Steel sheet piling composed of interlocking sections, each section comprising a web and having interlocks formed at the marginal side edges thereof to engage with complementary interlocks of an adjacent section, at least one of said interlocks being formed of a pair of flanges and one of said flanges being provided with a hook portion providing a shoulder adapted to coact with the interlock of an adjacent section to oppose longitudinal separation thereof, and a shoulder extension associated with

5 said hook portion and adapted to engage with a portion of the adjacent section to reinforce said hook portion against deflection under longitudinal stress substantially as described.

11. Steel sheet piling composed of interlocking sections, each section comprising a web having interlocks formed along the marginal side edges thereof and adapted to 10 engage with complementary interlocks of an adjacent section, at least one of said interlocks being formed of a pair of flanges, one of said flanges being provided with a hook portion providing a shoulder having 15 a surface approximately perpendicular to the longitudinal axis of the section to be engaged by the interlock of an adjacent section and opposing a longitudinal separation thereof said hook portion having an outwardly directed shoulder extension associated therewith and adapted to engage with a surface of the adjacent section to reinforce 20 said hook portion against deflection under longitudinal stress substantially as described.

12. Steel sheet piling composed of interlocking sections, each section comprising a web having a locking member and a guard flange at each edge thereof adapted to engage 30 similar members of like form on the adjoining sections, the locking members of adjoining sections being free to turn upon each other between said guard flanges to permit of angular arrangement of the sections and the locking members being formed 35 with hook portions having outwardly directed shoulder extensions associated therewith and adapted to engage with the guard flanges of an adjacent section thereby to reinforce the hook portions against deflection under longitudinal stresses substantially as described.

13. Metal sheet piling composed of interlocking sections, each section comprising a 45 web having a locking member and a guard flange at each edge thereof adapted to engage similar members of like form on an adjoining section the locking members of adjoining sections being free to turn about each other between said guard flanges to 50 permit of angular arrangement of the sections and said locking members being provided with opposed hooked portions arranged approximately at right angles to the longitudinal axis of the web and outwardly directed shoulder extensions associated with the hooked portions and adapted to engage an opposed surface of a guard flange of an adjacent section and one of said 55 shoulder extensions being arranged substantially in the line of longitudinal stress upon said hook portion whereby the latter is reinforced against deflection substantially as described.

14. Metal sheet piling composed of interlocking sections, each section comprising a web having a locking and a guard flange at each edge thereof adapted to engage similar members on the adjoining section, said locking flange being formed with a hooked portion and outwardly directed shoulder extensions associated therewith one of said shoulder extensions being disposed in the line of longitudinal pull on said hook portion and adapted to engage the guard flange of an adjacent section to reinforce 70 said hook portion from deflection under longitudinal stress, the inner surface of said guard flanges and the outer surfaces of said shoulder extensions being arranged substantially concentric with each other and with the contact surface on said hook portions whereby the hooks are free to turn upon each other to permit of angular arrangement of the sections substantially as described. 80

15. Metal sheet piling composed of interlocking sections, each section comprising a web having a locking and a guard flange at each edge thereof adapted to engage similar members on the adjoining section, said locking flange being formed with a hooked portion and outwardly directed shoulder extensions associated therewith one of said shoulder extensions being disposed in the 90 line of longitudinal pull on said hook portion and adapted to engage the guard flange of an adjacent section to reinforce said hook portion from deflection under longitudinal stress, the inner surface of said guard flanges and the outer surfaces of said shoulder extensions being arranged substantially concentric with each other and with the contact surface on said hook portions whereby the hooks are free to turn upon each 95 other to permit of angular arrangement of the sections and said hook and guard flanges being arranged to form enlarged grooves so as to provide pockets for disposed material and said hook portions being formed 100 with grooves intermediate of the shoulder extensions thereby to provide supplemental pockets substantially as described. 105

16. Metal sheet piling composed of interlocking sections, each section comprising a 115 web having a locking and a guard flange at each edge thereof adapted to engage similar members on the adjoining section, said locking flange being formed with a hooked portion and outwardly directed shoulder extensions associated therewith one of said shoulder extensions being disposed in the line of longitudinal pull on said hook portion and adapted to engage the guard flange of an adjacent section to reinforce said hook portion from deflection under longitudinal stress, the inner surface of said guard flanges and the outer surfaces of said shoulder ex- 120 125

- tensions being arranged substantially concentric with each other and with the contact surface on said hook portions whereby the hooks are free to turn upon each other
- 5 5 to permit of angular arrangement of the sections and said hook and guard flanges being arranged to form enlarged grooves so as to provide pockets for disposed material and said hook portions being formed with
- 10 10 grooves intermediate of the shoulder extensions thereby to provide supplemental pockets and each of said sections being formed with the hook flanges upon one side of the longitudinal axis of the web and the
- 15 15 guard flanges to the opposite side thereof substantially as described.
17. Steel sheet piling composed of interlocking sections, each section comprising a web and having interlocks along the vertical marginal side edges thereof adapted to interlock with the complemental interlocks of an adjacent section, said interlocks being each composed of coacting hook and guard flanges adapted to form a socket to
- 20 20 receive a hook flange of an adjacent section and at least one flange of each interlock being provided with a plurality of outwardly directed shoulder extensions in opposed relation to a surface of a flange of an adjacent
- 25 25 section interlocking therewith, substantially as described.
18. Steel sheet piling of double interlocked type composed of interlocking sections having at least one flange of each interlock formed with a longitudinally extending groove having its open side opposed to and closed by a portion of the adjacent section interlocked therewith thereby to provide
- 30 30

supplemental pockets in the interlock for improving the water-tight qualities thereof. 40

19. Steel sheet piling composed of interlocking sections, each section comprising a web and having interlocks along the vertical marginal side edges thereof adapted to interlock with complemental interlocks of 45 an adjacent section, said interlocks being each composed of coacting hook and guard flanges adapted to form a socket to receive a hook flange of an adjacent section and the hook flange of each interlock being formed 50 with a longitudinally extending groove having its open side opposed to and closed by a portion of the adjacent section interlocked therewith thereby to provide supplemental pockets in the interlock for improving the 55 water tight qualities thereof.

20. Steel sheet piling composed of interlocking sections, each section comprising a web having interlocks along the vertical marginal side edges thereof adapted to interlock with 60 complemental interlocks of an adjacent section, said interlocks being each composed of co-acting hook and guard flanges adapted to form a socket to receive a hook flange of an adjacent section and the hook flange 65 of each interlock being formed at its outer side with a longitudinally extending groove having its open side opposed to and closed by the guard flange of the adjacent section interlocked therewith thereby to provide 70 supplemental pockets in the interlock for improving the water tight qualities thereof.

In testimony whereof I have signed my name to this specification.

CHARLES SLAUSON BOARDMAN.
